FORMING MEANS

Joseph Miotke, Milwaukee, Wis.

Application April 29, 1932. Serial No. 608,221

11 Claims. (Cl. 113—44)

This invention relates to forming sheet metal objects by progressive steps wherein varying dies transform a closed tubular element employed as the base stock.

5 The objects of the invention are:—

The providing of means whereby a tubular sheet metal object is peculiarly shaped so that its physical properties and stability are preserved intact through the use of instrumentalities which require a fluid medium in certain steps of a progressive series of operations necessary in order to obtain a specifically designed article.

15 The offering of means whereby a singular and regularly cylindrical tube is partially elongated, tapered and then arcuately bent to assume a reverse-curve aspect beyond its original cylindrical shape, or other forms approximating the first recited design, wherein occur the necessity for imparting curved and tapering aspects to a hollow element having one of its two ends sealed until the several necessary operations are completed.

25 The means employed are disclosed in the accompanying drawings, to which the following specification and appended claims refer. The various figures are indexed as follows:—

Fig. 1 is a sectional side elevation of the initial forming step.

30 Fig. 2 is a similar elevation of the second step.

Fig. 3 is a section on line 3—3 of Fig. 2.

Fig. 4 illustrates the forming or closed position of the third step.

35 Fig. 5 is an open view of Fig. 4.

Fig. 6 is a sectional view of a tube at the line 6 of Fig. 4.

Fig. 7 is the fourth forming step.

40 Fig. 8 is the fifth and final forming step.

Fig. 9 is a detail of a fluid sealing means employed in the first and final steps, Fig. 1 and Fig. 2.

Fig. 10 is an alternative sealing means.

45 Fig. 11 is a perspective of the original tube or base stock.

Fig. 12 is the result obtained from the first step.

50 Fig. 13 is the result obtained in the second step.

Fig. 14 shows an approximate view of the product worked after the fourth step.

55 Fig. 15 shows the final result obtained in the fifth step, with the ultimate aspect indicated by dotted lines.

Similar characters of reference apply to like features throughout the several figures.

The disclosures are, in a sense, diagrammatic; the ultimate details of tool equipment have been omitted to leave only the essential elements which will answer the purpose here concerned. The various mechanical appurtenances actually required, as well as the various programs of those progressive methods necessary to the handling of the product worked, are numerous, and subject to such mechanical preferences as will best suit the kind of work performed and the kind of product worked in order to get the respective results desired. The present disclosure confines itself to a pouring-spout-like element, but it is here remarked that the said product or object may be other forms requiring like treatment for shaping articles of the tubular and hollow sheet metal variety in order that the costly methods now in vogue will be eliminated, as well as offering a stronger, smoother, and a more regularly contoured product having such curvatures as will readily fall within the class of designs equivalent to the chosen specimen.

Referring to the drawings, Fig. 1 comprises forming-press elements opposingly arranged to offer a divided and arcuately contoured angular cavity C formed by a fixed die-block 1 and a movable die-block 2, the latter slidably mounted in a suitable bed-block B wherein the ways B', which function as guides that direct the said movable block whose actuating elements include appropriate levers and linkage means 3 pivoted to the block 2 at 4. When locked in abutting relation the aforesaid blocks 1 and 2 provide the aforesaid angular cavity whose major leg forms a cylindrical bore C' wherein is slidably shiftable a spherically concaved piston 5 arranged to slide as an abutment which recedes under a pressure opposed by a resilient means 6, encompassing the piston's stem 7. The piston and stem means may be cushioned as shown, or by any other suitable arrangement which may be regulated to efficiently function as a resisting stop that will give way under a certain pressure and at a desirable speed necessary to accord with a product being worked or formed by the assembly. The vertical leg C'' of the said cavity is disposed to axially align with a fixed bore 8 wherein reciprocates a plunger P. The said figure discloses a condition obtaining at the end of an initial operation on the product or tube T, Fig. 11, which has been angularly bent as seen in Fig. 12. The next movement is to raise the plunger P to clear the cavity portion 100

C'' and the bore 8, withdraw the block 2 towards the left, to where the formed product may be easily removed through a gap 9 during which time the piston 5 functions as a knock-out means. The stock article or product T, shown as Fig. 11, is a sheet metal tube provided with a closed end T', of spherical aspect, which nests within the like concavity fashioned in piston 5. The meeting relation between tube 10 and piston occurs adjacent the elbow t of the said cavity, where the piston, shown dotted, has been advanced to meet said tube. The tube or product T, in the present operation, is filled with a fluid f to within a predetermined distance from its open end. It is then inserted in the bore 8 as shown dotted. The plunger's reduced end P' is supplied with an appropriate sealing disc S which compresses the said fluid to where a shoulder P'' abuttingly meets a circular brim c of the tube's open end. With the fluid f compressed as a solid in the tube the said plunger descends to where the spherical end T' enters the cavity of the piston 5 and from this meeting forward both piston and tube 25 remain in their nested relationship until the product is formed as this step intends. The ductility of the metal tube T, the accuracy of the cavity's contours, the cushioned opposition of the said piston, and the flexible, while solid, 30 characteristic of the fluid content, combine to produce an arcuately angular tube of uniform diameter and unchanged gauge thickness, which will be free from wrinkles, strains, or thinning stretches of the metallic body. This is possible 35 by virtue of the receding behavior of the piston 5 which is in keeping with the tube's advance into the cavity C, thereby preventing any inordinate straining of said tube when undergoing the initial change just described. The sealing of the fluid may or may not be exactly as 40 shown; either of the disclosed methods shown in Figs. 9 and 10 will produce equally satisfactory results whether the element S be a separate or an attached disc. Individual discs S' 45 may be placed in a number of the tubes and these discs trued up to seal the fluid effectively upon entrance of the reduced end P'. The forming result, as completed by the foregoing operation, is termed X, Fig. 12.

50 The bent tube X is next subjected to forming changes produced by the assembly illustrated in Fig. 2. A suitable bed-block 10 and its divided die-block 11-11' are arranged to form an angular cavity Ca wherein occurs a mandrel 12 which latter is held in a non-rotative and accurately centered relation within the said cavity by means of a flanged and hardened bushing 13 and a forked form of pivoting 55 14 where the mandrel is connected to a flat link element 15 and actuated by suitable means including a bell-crank lever 16 or any other appropriate hook-up. The mandrel 12 has a semi-spherical terminous or nose 12' which coincides with the elbow formation t' of the previously bent tube T. The section 3-3, Fig. 3, shows the divided blocks 11-11' articulated, or hinged together at ha, and provided with a lock-means in the form of a hook h which latter shoulders under the ledge 11b. This arrangement forms a clamp which holds the cylindrical portion T' of the tube where its brim c will abut the flange 13' of the bushing 13, and resist tendencies to move when subjected to forces resulting from the pressures applied in 60 70 75 tapering a portion of the tube T. The result

of the first operation X is inverted in the cavity Ca to bring the brim c against said flange while the block 11 is swung open as arrow indicates in said Fig. 3, the blocks 11-11' are then latched, leaving the closed end of the tube T' extended above the blocks. The said tube is inwardly clamped in the position shown by the elbow-pinching contact of the snugly fitting mandrel nose 12'. While held as described, the tube's closed end extending above the die-blocks is subjected to the tapering influences of separate but similar die-punches Pa whose conical bores Pa' will offer a series of varying tapers which compel the upstanding portion of the tube T to be elongated by a series of compression steps, as shown dotted, until the object X takes the form disclosed as Xa in Fig. 13. The tapering steps performed by the separate die-punches Pa will vary in number and degree of taper with the variable ductile characteristics residing in the particular product worked; here the steps are indicated as X1, X2 and X3. The just described operation, or second step, does not require a fluid medium. When completed the object Xa is easily removed by raising the punch, unlatching the hook h, and withdrawing the mandrel 12, as lever arrow in Fig. 2 indicates. Each punch, it will be noted, has a conically bored apron Pa'' arranged to snugly fit about the perfect circle, or regular tube form at elbow t', thereby outwardly cooperating with the inwardly disposed mandrel nose 12' to prevent distortion of the hollow tubular elbow immediately under the punch. 80 85 90 95 100 105 110 115 120 125 130 135 140 145 150

Figs. 4 and 5 disclose a tapered tube bending arrangement by which the object Xa, just described, is given an "ogee" or reverse-curve aspect along the tapered neck X3. Die-blocks 17 and 17' are pivoted to rock about their respective pivots 18 and 18', fixed in a base 19. The said blocks are each provided with structurally integral gear segments 20 and 20' which intermesh to assure a positive and uniform angularity in said blocks when a plunger-like die-block 21 descends upon the formed product Xa in order to affect the curvature noted. The blocks 17 and 17' and 21, when in forming relation, are grooved out as shown to provide a curved and tapering bore which is determined to have a purposeful contour that affects the object Xa so that same will be somewhat malformed intentionally along the arcuate taper portion X3' which this operation produces, in order to get the desired sweep of the ogee bend, but still restrained by the said bore's formation in order to prevent an inordinate crushing or flattening of the tubular spout beyond a metal fatiguing phase which might prevent the sinuously curved portion from being, later on, pressed back into an unimpaired but irregular circular cross-sectional aspect after said mal-forming has imparted a noticeable but helpful transverse elliptical outline. The block 17 is provided with a boss 22 over which the regularly circular brim c is slipped, leaving the elbow T' to snugly fit around the form of the block's grooved surface which is accurately concentric to said elbow turn which relationship preserves the open end and the elbow parts of the object Xa unchanged by the operation performed with the assembly seen in Fig. 4. The product of this operation is indicated as Xb in Fig. 12 and the distortion occurring there-in is disclosed in Figs. 6 and 7. 150

Fig. 6 shows the sectional aspect at the medial bent area of the object Xb , indicated by the line "6" of Fig. 4 where the tube has been excessively crushed $X3'$ to get the longitudinal curvature desired.

Fig. 7 shows the fourth step which is an operation requiring the application of simple forming die-blocks 23 and 24, movable as per arrows, which restore the elliptical aspect, $X3'$, back to the circular form shown dotted in said figure.

The operations of the third and fourth steps produce irregularities in the form of slight bulges and shallow waves in the metal handled which are eliminated in Fig. 8 which is the last forming operation. The procedure here is similar to the initial step of Fig. 1. An accurately formed and smoothly finished cavity Cd is produced by a slidable die-block 1' and a stationary block 2'. While the former block is withdrawn the object Xb is inserted as shown, fill in this instance with a fluid f' . The tubular portion T' projects beyond the blocks 1' and 2' when a ram-like plunger R envelops said portion simultaneously with the entrance of a plunger R' having a sealing disc Sa that functions similarly to the like means P' and P'' of Fig. 1. The ram offers a shoulder R'' which abuts the brim c and the pressure exerted compels the fluid f' to force the metal wall of the tube element to take the form of the aforesaid cavity, and eradicate all traces of the irregularities resulting from the third and fourth operations, thereby producing the object seen in Fig. 15.

The commercial object will have a flange m , and the closed end of the tube will then be cut open, as at n ; these additional features are further operative steps produced by well-known methods which need no recital here.

The several assemblies performing the foregoing steps may be grouped in closely related orders of sequence that will simplify and speed up production. The essential concern here is; the moderation of applied stresses to which the sheet-metal product is subjected, the equally moderate and progressive changes made, all allow said metal to flow easily into the shapes taken, which changes do not, at any stage, stretch or crowd the stock into lessening or thickening the original metal gauge, thereby minimizing "seconds" or "culls". This accomplishment produces an object of uniform strength throughout, and offers a smooth surfaced hollow article that requires a minimum of finishing and polishing treatment for arriving at the commercial finality indicated in Fig. 15. The said commercial article will, however, have the additional features already noted. The aforesaid article may also be designed in a variety of styles which remain similar in their general curvatures. It will also be obvious that a variety of sheet metal items can be produced other than the specific spout here selected for disclosure purposes. Further, the metallic or physical properties of the stock may be sheet steel, aluminum, or like product wherein resides a ductility necessary in the sheet-metal, or equivalent, arts.

Having described the invention what is desired to claim and protect by United States Letters Patent, is:—

1. Forming means having, a sheet metal tube forming assembly embodying a reciprocative die-cavity-completing block abutting a fixed die-block to form a piston bore, a piston element resiliently reciprocative in said bore for resisting distortion of a tubular object fashioned

under an endwise pressure that is opposed by said piston, said piston functioning as a tube ejector when the aforesaid assembly is opened.

2. Forming means having, an angularly contoured cavity, a plunger axially reciprocative in aligned relation over the entrance of said cavity, tube centering means, tube abutment means within said cavity, said centering means maintaining the cylindrical aspects of said tube during the descent of said plunger and after said plunger has entered the aforesaid centering means.

3. Forming means having, opposingly grooved and separable members forming a cylindrical bore, said bore receptive to an enterable fluid sealing plunger, a resiliently urged piston element opposing said plunger when spaced therefrom by a fluid charged tubular product that fills the bore between said plunger and the aforesaid piston element.

4. Forming means having, a slidable and a fixed die-block abutting each other to form an angular tube-accommodating cavity, plunger means subject to power thrusting shouldering against and sealing the open end of a fluid filled tube in said cavity, and a spherically concaved piston element abutting the said tube in axial alignment throughout the said tube's tenure in said cavity.

5. Forming means having, an angular tube receiving cavity formed in divided die-blocks, said cavity contoured to accommodate an elbow formation on said angular tube, a mandrel filling the bore of said tube and terminated to provide an interiorly disposed gripping nose formation registering with the said elbow formation for resisting longitudinal shifting of the aforesaid tube.

6. Forming means having, angularly bent tube-holding die-blocks providing an interiorly disposed plunger-like clamp, superposed plunger means axially aligned to reciprocatively wipe a tubular product outwardly projecting beyond said blocks, graduated taper-forming bores residing in said means, said bores functioning to progressively taper and lengthen the projected portion of said product.

7. Forming means having, conically tapered forming plungers reciprocatively aligned with a projecting tubular product, said product held by a die-block and clamped at an elbow formation within said block, a removable ram element locking said tubular product within said block to oppose a downward pressure offered by said plungers, said plungers progressively encompassing said product in descending steps and compressing said tubular product to vary its conically changed aspect, said plungers effecting elongation of said product above the aforesaid die-block.

8. Forming means having, a singular die-plunger, pivoted die-block members geared together to rock in unison forming an angular tube-shaping abutment, said blocks rockably responsive to pressure applied by said plunger to leave an object intermediate the plunger and die elements arcuately free across the abutting plane of said die-blocks.

9. Forming means having, a divided arcuate cavity formed of opposingly tiltable die-blocks and an opposingly grooved plunger-die, a hollow dowel stud element on one of said blocks for positioning the elbow portion of a hollow tubular object tapered beyond said portion, said blocks divided medially of the tapered portion's

length, the said dowel functioning as a tube anchorage that preserves the cylindrical aspects of said tube when the plunger-die descends to force the said blocks into opposed angular relationship in bending the aforesaid tapered portion.

10. Forming means having; a taper-forming operation providing a tube holding cavity; an annular tube-rim abutment within said cavity; an articulated die-block, forming a portion of said cavity, lockable as a clamp about a cylindrical tube element at the aforesaid abutment; a mandrel plunger within said cavity, said mandrel preserving the cylindrical form of the tube

15

element in opposition to the clamping pressure of said articulated die-block.

11. Forming means having, a divided die-block assembly offering a definite cavity, a liquid filled tubular element imperfectly corresponding to said cavity, a dual plunger respectively abutting a rim of said element and sealing the liquid in said element, said plunger functioning as a pressure ram for simultaneously forcing said element into the aforesaid cavity and compelling same to expand and assume the contour of the aforesaid definite cavity.
